COMBINATION ROD SAFETY JOINT AND
TUBING DRAIN

John S. Page, Long Beach, Calif.

Application November 18, 1941, Serial No. 419,556

13 Claims. (Cl. 103—221)

This invention relates to well production equipment and relates more particularly to a combination sucker rod safety joint and tubing drain. A general object of this invention is to provide practical, effective and dependable well production equipment of the character referred to which materially facilitates the removal and replacement of the well pump and sucker rods.

Another object of this invention is to provide a combination sucker rod safety joint and tubing drain which permits the withdrawal of a free pump without the necessity of draining the tubing and which provides for the controlled or restricted draining of the oil tubing when it becomes necessary to remove the tubing to recover a "sanded up" pump. When the necessity arises to remove a pump for replacement or to fish out a broken sucker rod it has always been a former practice to merely pull the pump from its anchor and allow the long column of oil standing in the tubing to suddenly rush back into the well. This sudden and forcible return of a large volume of oil disturbs the oil sands and the sudden reverse flow of the oil into the formation often results in a sustained or even permanent reduction in the rate of production when pumping is resumed. The equipment of the present invention completely avoids the sudden uncontrolled "dumping" of the oil back into the well and permits the pump to be pulled without disturbing the oil sands. In the present state of the art a foot valve is frequently installed below the pump so that the column of oil standing in the tubing will not be released to rush back into the well when the pump is removed. However, where a foot valve of this kind is used and the pump becomes sanded up so that it cannot be removed it is impossible to drain the column of oil from the tubing and it is necessary to perform a wet job when the tubing is removed. When the equipment of the present invention is employed a foot valve may be installed below the pump so that a free pump may be removed without releasing the column of oil standing in the tubing and equipment of the invention provides for the controlled draining of the oil column from the tubing when it becomes necessary to withdraw the tubing string to remove a sanded up pump.

Another object of this invention is to provide equipment of the character mentioned which avoids the necessity of priming the new or replacement pump following its installation and which assures the operation of the new or replacement pump in clean oil. When the equipment of the present invention is employed the

new pump is lowered into clean oil standing in the tubing and is therefore effectively lubricated and immediately primed, thus preventing injury to the new pump and eliminating a time consuming priming operation.

Another object of this invention is to provide a combination sucker rod safety joint and tubing drain which provides for the draining of the tubing without lifting or in any way disturbing the tubing string. In accordance with the present invention the tubing may be drained by simple manipulation of the sucker rod string, thus avoiding the necessity of lifting the tubing which is liable to part or fail by reason of the great weight of the oil column standing in it.

Another object of this invention is to provide a combination sucker rod safety joint and tubing drain which permits the rod joints to be "screwed back" or tightened from time to time without the possibility or danger of releasing the safety joint. The pumping motion of the sucker rod has a tendency to unscrew the rod joints and it is a general practice to rotate the sucker rod string to the right from time to time to tighten up any joints that may become loose. The safety joint of the present invention is not unthreaded or released by the rotation required to tighten the rod joints and the safety joint is such that a desirable weight may be maintained on the string of sucker rods when the rod joints are tightened in this manner.

Another object of this invention is to provide a combination sucker rod safety joint and tubing drain that avoids the wet jobs usually accompanying the pulling of the tubing and rods. It has been the general practice when a pump has become stuck or sanded up to rotate the string of sucker rods to the left from its upper end to unscrew one of the rod joints and then pull out the rod sections above the joint. The tubing string containing the column of oil is then hoisted up and its joints are successively disconnected at the ground surface until the portion of the rod remaining in the tubing is made accessible. The successive disconnection of the tubing sections allows the oil in the sections to spill out at the surface. When the upper end of the rod which remains in the tubing is accessible the rod is again rotated to the left to unthread as much of the rod as possible and the rod portion thus freed is withdrawn. These operations are repeated until the entire rod and tubing are removed. This is a long tedious operation and is accompanied by the loss of the oil that was standing in the tubing and the oil spilled into the derrick creates a hazard and makes the work slow and dangerous.

With the equipment of the present invention the tubing string may be drained before pulling the rod and the pump and there is never the necessity for a wet job.

Another object of this invention is to provide a combination sucker rod safety joint and tubing drain in which the tubing drain does not embody slips or other casing engaging means. The drain section embodied in the invention is no larger in external diameter than the other joints of the tubing string and, therefore, does not engage the casing or interfere with the free "working" of the tubing when the pumping operation is in practice. The drain section being no larger than the couplings of the tubing allows the tubing to be pulled through an oil saver under pressure.

Another object of this invention is to provide equipment of the character referred to that is positive and that will not release the rod from the pump or allow the oil to drain from the tubing except when the rod is intentionally manipulated for this purpose.

Another object of this invention is to provide equipment of the character referred to in which the safety joint positively transmits axial forces in both directions so that there is no slack or play in the string.

Another object of this invention is to provide equipment of the character referred to in which the tubing drain means does not obstruct or restrict the tubing and is not worn by the pumping motion of the sucker rod in the tubing.

A further object of this invention is to provide equipment of the character mentioned which is inexpensive to manufacture and install and which is convenient to operate.

The various objects and features of my invention will be fully understood from the following detailed description of a typical preferred form and application of my invention, throughout which description reference is made to the accompanying drawings, in which:

Fig. 1 is a more or less diagrammatic view of the apparatus of this invention installed in the operative position in a well with the well pump in operation, the tubing string and tubing drain appearing in longitudinal cross section. Fig. 2 is a view similar to Fig. 1 showing the parts following the release of the safety joint and illustrating the tubing drain being opened. Fig. 3 is an enlarged longitudinal detailed sectional view of the safety joint in the operative condition, that is, in the condition where the pump is in operation. Fig. 4 is a view similar to Fig. 3 with a portion in elevation to illustrate the clutch parts in engagement and showing the joint elements conditioned for the release of the joint. Fig. 5 is an enlarged fragmentary longitudinal detailed sectional view showing the blades of the safety joint assembly in engagement with the drain sleeve preparatory to opening the drain. Fig. 6 is an enlarged transverse detailed sectional view taken as indicated by line 6-6 on Fig. 3. Figs. 7 and 8 are enlarged transverse detailed sectional views taken as indicated by lines 7-7 and 8-8, respectively, on Fig. 4 and Fig. 9 is an enlarged perspective view of one of the blades.

The tools or equipment of the present invention may be said to comprise, generally, a drain means 10 connected in the tubing string T operable to allow the fluid to drain from the tubing, means 11 on the sucker rod string R operable to open the drain means 10 and a releasable safety joint 12 interposed in the sucker rod string R and releasable to free the means 11 for operation

and to permit the free withdrawal of the major portion of the rod string.

The drain means 10 is interposed in the string of tubing T to provide for the draining of the oil or liquid from the tubing. In practice, the drain means 10 may be provided in the tubing T at any selected point. It is preferred to space the drain means 10 some distance above the pump P where there will be no danger of the drain means becoming sanded up. In the preferred construction the drain means 10 includes an elongate tubular coupling or body 13. One end of the body 13 may be threaded directly onto a section of the tubing T. In the construction illustrated the upper end of the body 13 is directly screwed onto the lower end of a tubing section 14 and the lower portion of the body 13 is screwed onto a sub 15 which in turn is threaded to a lower tubing section 14. It is preferred to provide gaskets 16 between opposing shoulders of the body 13 and sub 15 to provide a tight seal between the body and sub.

It is a feature of the invention that the external diameter of the body 13 need be no greater than the external diameter of the regular couplings of the string of tubing T. The internal diameter of the tubular body 13 is considerably larger than the internal diameter of the tube sections 14. A series of circumferentially spaced ports 17 is provided in the wall of the drain section or body 13. The series of ports 17 is spaced between the ends of the body 13 and the ports are directed downwardly and outwardly so that the fluid discharged from them does not blast against the casing. There may be any selected number of ports 17 of selected capacity. In most instances it is preferred to limit the aggregate capacity of the ports 17 to prevent a sudden or rapid discharge of the fluid from the tubing. It will be observed that the drain section or body 13 is a simple element readily connected in the string of tubing T between two adjacent tubing sections 14 at any selected or required point along the string.

The drain means 10 further includes a sleeve 18 for controlling or closing the ports 17. The sleeve 18 shiftably or slidably engages within the body 13 and is of substantial length. The internal diameter of the sleeve 18 is preferably somewhat greater than the internal diameter of the tubing sections 14 so that there is little or no tendency for the sucker rod R to engage the sleeve as the rod reciprocates during the pumping operation. External annular grooves 19 are provided in the sleeve 18 adjacent its opposite ends. Flexible resilient sealing rings 20 are provided in the grooves 19 to seal with the internal surface of the body 13. The outer ends of the sealing rings 20 are grooved to have lips 21 which are urged into effective sealing engagement with the internal surface of the body 13 by the fluid pressure. The sealing rings 20 are spaced apart to be above and below the series of ports 17 when the sleeve 18 is in its normal or closed position illustrated in Figs. 1 and 5. The engagement of the sleeve 18 and its rings 20 in the body 13 is such that the sleeve will not shift or move until there is the deliberate application of force to move it. The sleeve 18 is adapted to be shifted downwardly to a position where it engages against the upper end of the sub 15 and when the sleeve is in this position the ports 17 are clear or uncovered.

The means 11 is carried by or associated with the safety joint 12 and when conditioned for op-

eration it is operable to apply downward force to the sleeve 18 to move the sleeve to an open position where the ports 17 are uncovered. The means 11 is initially or normally held refracted and inoperative by an element of the safety joint 12 and is not freed or released for operation until the safety joint is "broken" or disconnected. The safety joint 12 includes upper and lower body sections A and B and the means 11 is carried by the upper joint section A. The upper section A is provided at its upper end with a tapered threaded pin 22 and flat faces 23 to facilitate its connection with the adjacent length of sucker rod R. The joint section A has a transverse opening or slot 24 below the faces 23 for receiving or housing the means 11. The slot 24 is elongated longitudinally of the safety joint and has flat vertical side walls.

The means 11 includes a pair of blades 25 pivotally mounted in the slot 24. The blades 25 are vertically disposed elements having flat vertical side faces. The blades 25 are arranged in side by side relation with their inner surfaces in opposition and engagement and with their outer surfaces at or engaging the side walls of the slot 24. The longitudinal edges of the blades 25 are straight and flat and each blade has a rounded lower corner 34. A transverse opening 26 is provided in the joint section A to intersect the upper portion of the slot 24. A screw or pin 27 is secured in the opening 26 to pass through the slot 24 and to extend through transverse openings 28 in the upper portions of the blades 25. In practice, the screw 27 may be threaded in the opening 26 at one side of the slot 24 and may have its head received in the opening 26 at the other side of the slot. The pin or screw 27 extending through the opening 28 supports the blades 25 for free pivotal movement about a horizontal axis.

Means is provided to automatically swing the blades 25 outwardly and upwardly. As best illustrated in Fig. 9 the inner side of each blade 25 has a socket 30 concentric with its opening 28 and has a lateral slot 31 joining its socket 30. The sockets 30 of the two blades are in communication or registration. A torsional spring 32 surrounds the pin or screw 27 and is housed in the registering sockets 30. The spring 32 has straight end parts 33 which engage or bear in the slots 31 to urge the blades 25 outwardly and upwardly. The arrangement of the blades 25 and spring 32 is such that the spring swings the blades from opposite sides of the joint section A, that is, one blade is swung from one side of the section and the other blade is swung from the other side of the section. The edges of the blades 25 are adapted to swing up against the flat upper wall of the slot 24 and this wall stops the blades in positions where their lower edges are substantially horizontal and in a common plane. When the blades 25 are extended their rounded corners 34 face upwardly and serve to prevent the blades from catching in the tubing couplings when the string of sucker rod R is withdrawn from the tubing, as will be later described.

The safety joint 12 constitutes a connection in the sucker rod string R that remains connected or coupled throughout all the regular pumping operations but which may be readily released when it is desired to withdraw the sucker rod and drain the tubing T preparatory to pulling the tubing. The safety joint comprises the two sections A and B referred to above connected between the adjacent sections of the rod R at a selected point above the pump P. The upper

section A is connected in the sucker rod string R by the tapered pin 22 referred to above, while the lower end of the lower section B has a tapered socket 35 for receiving the threaded pin 36 of a length of sucker rod. The sections A and B are elongate cylindrical members preferably of the same external diameter. The threads of the several connections in the sucker rod string R are usually right hand threads and in the present disclosure it will be assumed that the threads of the sucker rod string are all right hand threads.

A longitudinal opening 37 is provided in the lower portion of the upper section A and the lower section B has a central longitudinal opening 38 which registers with the lower end of the opening 37. The opposing ends of the joint sections A and B are provided with clutch parts X and Y, respectively, adapted to engage or mesh for the transmission of torque and to prevent bodily turning of the sucker rod string R during certain phases of the operations, as will be later described. The clutch parts X and Y are adapted to mesh one with the other to prevent relative turning between the sections A and B in either direction. In accordance with the invention the ends or crests of the clutch parts A and B are flat and adapted to bear one on the other to prevent relative axial movement between the sections A and B in one direction. In the preferred construction the crests of the clutch parts A and B are flat and horizontal as illustrated throughout the drawings. Fig. 1 illustrates the manner in which the clutch parts X bears on the clutch parts Y for the transmission of downward force from the section A to the section B.

The safety joint 12 further includes an inner section or inner member C. The inner member C is slidably and turnably received in the opening 38 of the lower section B. An enlarged head 40 is provided on the lower end of the member C to slidably engage in the enlarged lower portion of the opening 38. The wall of the opening 38 has an annular shoulder 41 facing downwardly to oppose the upper end of the head 40. The member C extends upwardly from the lower joint section B and its upper portion constitutes a stem 42 which is threaded in the opening 37 of the upper joint section A. The threads 43 on the wall of the opening 37 and the stem 42 are left hand threads, that is, they are pitched in the opposite direction to the threads of the other joints in the sucker rod string R. The relationship of the parts is such that the upper end of the head 40 is in cooperation with the shoulder 41 when the crests of the clutch parts X and Y are in engagement. The engaging crests of the clutch parts X and Y are operable to transmit downward force from the section A to the section B, while the upper end of the head 40 engaging the shoulder 41 is operable to transmit upward force from the section A to the section B. Thus, when the parts are in the position illustrated in Fig. 1 of the drawings, the safety joint is capable of positively transmitting axial force in both directions.

The stem 42 of the member C carries an extension or pin 44 for controlling the blades 25 of the means 11. The pin 44 may be threaded in an opening in the upper part of the stem 42 or may be otherwise fixed to the stem. The reduced pin 44 extends or passes upwardly through an opening 44a in the section A to project into the slot 24. The lower or outer portion of each blade 25 has a socket or groove 45. The grooves 45 are open at the inner faces of the blades 25

when the blades are retracted the grooves 45 register to form an opening for receiving the pin 44. The engagement of the pin 44 in the grooves 45 dependably holds the blades 25 in the retracted positions where they are entirely within the slot 24.

The inner member C of the safety joint is connected with the lower section B for limited relative turning to permit or provide for the meshing engagement and disengagement of the clutch parts X and Y. The enlargement or head 40 of the inner member C has a circumferential groove 46. The circumferential extent of the groove 46 is considerably greater than the circumferential extent of any one of the clutch parts X and Y, which latter are equal in width, and the height of the groove 46 is considerably greater than the height of the individual clutch parts X and Y. A stop pin 47 is fixed to the section B and extends into the groove 46. In practice, the pin 47 may be fixed in an opening in the wall of the section B. When the crests of the clutch parts X and Y are in engagement, as in Fig. 1 of the drawings, the pin 47 is received in the forward end of the groove 46, relative to the right hand direction of rotation, and is in the lower portion of the groove.

Yielding spring means 48 is provided to urge the member C to the position where the crests of the clutch parts X and Y will engage when the section A is raised relative to the section B. A coiled torsional spring 49 is provided in the opening 38 below the head 40. The spring 49 has a tail 50 set in an opening in the pin 36 and has a tail 51 on its other end received in an opening in the lower end of the head 40. The spring 49 is under a torsional strain to urge the member C to turn to the right or in a clockwise direction relative to the section B. The spring 48 may be adjusted or set to exert substantial force on the member C so that the crests of the teeth are automatically brought into cooperation when the section A is raised with respect to the section B.

The combination tubing drain and safety joint may be employed in association with well pumps of various kinds. In Figs. 1 and 2 of the drawings I have illustrated in a diagrammatic manner the equipment employed with a typical well pump of the standing barrel and working plunger type. The pump P includes the barrel 52 removably fixed by an anchor 53 engaged in a shoe 54 on the lower end of the tubing string T. The plunger 55 of the pump is secured to the lower end of the sucker rod string R to be reciprocated thereby. In the case illustrated, the plunger 55 is directly connected with the section B of the safety joint, it being understood that in many instances the safety joint would be spaced above the pump plunger. A foot valve V is installed below the pump P to prevent the column of oil standing in the tubing from rushing back into the well when the pump P is removed.

Well pumps usually embody means for clutching the barrel and plunger against relative rotation so that the threaded joints of the sucker rod string R may be tightened or screwed up from time to time. In the particular case illustrated the upper end of the plunger 55 carries clutch parts 56 engageable with clutch parts 57 on the barrel 52. The clutch parts 56 and 57 are engaged by lowering the sucker rod string R and it is usual to allow some weight to rest on the string when it is rotated to screw up the joints.

In the use or operation of the equipment pro-

vided by this invention the coupling or body 13 of the drain means 10 is connected in the string of tubing T at the selected point before the tubing is run into the well. In a like manner the safety joint 12 carrying the means 11 is connected in the sucker rod string R when the same is made up and run into the well with the pump thereon. The safety joint and the means 12 are assembled to have the parts in the condition illustrated in Figs. 1, 3 and 4 of the drawings. The string of tubing T and the sucker rod string R are run into the well in the usual manner. During the pumping operation the sucker rod string R is reciprocated and the oil is pumped up through the tubing T in the well known manner. It is to be understood that during the pumping operation the pump barrel 52 remains anchored and the sleeve 18 of the drain means 10 remains in the closed position. During the pumping operation the parts of the safety joint 12 are in the positions illustrated in Fig. 1, the clutch parts X having their crests resting upon the tops of the clutch parts Y and the upper end of the head 40 being engaged with the shoulder 41. These relationships provide for the positive transmission of axial motion in both directions without play or slack. The torsional spring 49 serves to maintain the crests of the clutch parts X and Y in engagement.

The prolonged reciprocation of the sucker rod string R often tends to unthread or loosen the threaded joints of the rod. Accordingly, it is desirable from time to time to screw up the rod joints. To accomplish this the reciprocation of the sucker rod R is stopped and the rod is allowed to settle slightly and is turned to the right. A partial turn of the joint section A to the right relative to the joint section B engages the clutch parts X with the clutch parts Y, that is, the clutch parts are made to mesh one with the other. The weight maintained on the sucker rod maintains the clutch parts X and Y in meshing engagement and likewise maintains the clutch parts 56 and 57 in clutching engagement. Accordingly, the string of sucker rod R is held against turning from its lower end by reason of the pump anchor, the clutch parts 56 and 57 and the clutch parts X and Y. The sucker rod string R is turned to the right at the ground surface to tighten or screw up the threaded connections of the rod string. When this has been done the sucker rod string R is raised and the torque or turning force exerted by the spring produces relative turning between the sections A and B to bring the crests of the clutch parts X and Y into cooperation so that the equipment is again in condition for the pumping operation. In this connection it will be observed that the engagement of the upper end of the head 40 with the shoulder 41 stops or positions the section A where the crests of its clutch parts X will automatically engage the crests of the clutch parts Y between the relative turning between the sections A and B.

After extended operation of the pump P the pump may become worn so that its efficiency is impaired to the extent that it is necessary to withdraw the pump. The pump P is pulled free from its shoe 54 and the rod R and pump P are withdrawn from the well. The valve V retains the column of oil in the tubing T and the new or replacement pump may be seated in the shoe 54 to be primed and commence operation in the clean oil retained in the tubing.

Very frequently a pump will become sanded up

so that it cannot be pulled free. When this occurs the sucker rod string R is allowed to settle sufficiently to bring the pump clutch parts 53 and 57 into engagement and the sucker rod is turned a short distance to the right to bring the clutch parts X and Y into mesh. This slight turning of the section A with respect to the section B brings the member C to the position where the groove 46 is located as illustrated in Fig. 7 with the pin 47 spaced between the ends of the groove. A right hand strain or torque is then imposed on the string of sucker rod R. In practice, the upper end of the rod R may be turned several times to the right. The sucker rod string R is then raised to move the clutch parts X and Y out of mesh. When the clutch parts X and Y move out of mesh the torque imposed on the string, as above described, causes the section A to suddenly turn with respect to the section B. During the first stage of this sudden turning movement the rear wall of the groove 46 is forcibly brought against the stop pin 47 and the resultant jar or sudden stopping of the member C causes the threads 43 to break or free themselves. The member C is held against further turning to the right by the engagement of the pin 47 with the rear wall of the groove 46 and the torque that has been stored in the sucker rod string R may cause the section A to turn with respect to the member C to partially unscrew the threads 43. It is to be observed that if a substantial torque is stored in the sucker rod string R prior to the disengagement of the clutch parts X and Y the threads 43 may be entirely or substantially entirely unscrewed when the clutch parts are disengaged. In any case, the sucker rod string R may be rotated to the right from its upper end to complete unscrewing of the threads 43. The sucker rod string R is then raised. This completes the disengagement of the section A from the section B and immediately upon the pin 44 being disengaged from the blades 25 the spring 32 swings the blades outwardly.

Following the release of the safety joint 12 the sucker rod string R is raised a sufficient distance to bring the blades 25 to a point above the sleeve 18. In this connection it will be observed that the rounded corners 34 of the blades 25 allow the blades to move upwardly through the tubing T and sleeve 18 with a minimum of interference. When the blades 25 have been moved to a point above the sleeve 18 the sucker rod string R is moved downwardly or "spudded" to bring the lower edges of the blades 25 into engagement with the top of the sleeve 18 and to cause the sleeve to move downwardly. The sleeve 18 is moved downwardly to a position where it is clear of the ports 17. The sucker rod string R is then withdrawn from the well in the usual manner.

During the withdrawal of the sucker rod string R the column of oil standing in the tubing T is free to drain out through the ports 17. As above described, the ports 17 may be proportioned so that the discharge of the oil from the string is controlled or restricted to such an extent that the returning oil does not disturb the oil sands or create any appreciable turbulence in the well. In most instances, by the time the sucker rod string R has been pulled from the tubing T the oil will have drained from the tubing. The string of tubing T is then withdrawn from the well. In this connection it is to be observed that the drain means 10 does not have gripping engagement with the well casing and

does not interfere with the free pulling of the tubing. Further, it should be observed that the body 13 of the drain means is no larger in diameter than the couplings of the tubing string so that it may be pulled through an oil saver if this is necessary. The tubing T is withdrawn "dry," that is, the column of fluid is drained from the tubing prior to the pulling of the same and the tubing is relieved of the weight of the standing column. There is no oil spilled at the ground surface and there is no danger of the tubing parting by reason of the weight of a contained column of oil.

Having described only a typical preferred form 15 and application of my invention I do not wish to be limited or restricted to the specific details herein set forth, but wish to reserve to myself any variations or modifications that may appear to those skilled in the art or fall within 20 the scope of the following claims.

Having described my invention, I claim:

1. In combination, a well tubing, a normally closed drain means interposed in the tubing, a pump operating string extending through the tubing, a releasable joint in the pump operating string, and means made operative upon the release of said joint for opening the drain means.

2. Apparatus for use with a well tubing and a pump operating string which extends through 30 the tubing, the apparatus including a normally closed drain means for the tubing adapted to be opened to allow fluid to drain from the tubing, a releasable joint interposed in the pump operating string releasable by manipulation of the 35 string to allow withdrawal of a portion of the string, and means on said portion of the string for opening the drain means made effective only upon the release of said joint.

3. Apparatus for use with a well tubing and a pump operating string which extends through 40 the tubing, the apparatus including a normally closed drain means for the tubing adapted to be opened to allow fluid to drain from the tubing, a releasable joint interposed in the string 45 releasable by manipulation of the string to allow withdrawal of a portion of the string, and a projectable blade operatively connected with said joint operable when projected to open said drain means and projectable only upon the release of 50 the joint.

4. Apparatus for use with a well tubing and a pump operating string which extends through the tubing, the apparatus including a normally closed drain means for the tubing adapted to be opened to allow fluid to drain from the tubing, a releasable joint interposed in the pump operating string releasable by manipulation of the string to allow withdrawal of a portion of the string, means on said portion of the string operable to open said drain means, and means 60 for holding the last named means inoperative and released upon the release of the joint.

5. Well production equipment comprising a well tubing having a drain port, a pump carried by the tubing, and a pump operating string extending into the tubing, the equipment being characterized by a part normally closing the port and movable to a position where the port is open, a joint connecting portions of the pump operating string releasable by manipulation of the string, means on one of said string portions operable to engage and move said part, and means for holding the last named means retracted and freeing said last named means upon 70 the release of the joint.

6. Well production equipment comprising a well tubing having a drain port, a pump carried by the tubing, and a pump operating string extending into the tubing, the equipment being characterized by a part normally closing the port and movable to a position where the port is open, a joint connecting portions of the pump operating string releasable by manipulation of the string, a member projectable from the portion of the string above said joint operable to engage and move said part to the position where the port is open, and means normally holding the member retracted released upon the release of the joint.

7. Well production equipment comprising a well tubing having a drain port, a pump carried by the tubing, and a pump operating string extending into the tubing, the equipment being characterized by a sleeve in the tubing closing said port and movable to a position where the port is open, a joint interposed in the string releasable to allow withdrawal of the main portion of the string, a member projectable from said portion of the string and operable to engage and move said sleeve, and means for holding the member retracted and released to allow projection of the member upon the release of said joint.

8. Well production equipment comprising a well tubing having a drain port, a pump carried by the tubing, and a pump operating string extending into the tubing, the equipment being characterized by a sleeve in the tubing closing said port and movable to a position where the port is open, a joint interposed in the string releasable to allow withdrawal of the main portion of the string, a member projectable from said portion of the string and operable to engage and move said sleeve, spring means tending to project the member, and means for holding the member retracted and released to allow projection of the member upon the release of said joint.

9. Well production equipment including a pump operating string comprising a multiplicity of screw threaded parts, and a safety joint for the string comprising two sections to be interposed in the string, screw threads on the sections for securing the sections to spaced parts of the string, a member releasably screw threaded with one section, means connecting said member with the other section for limited relative turning and limited relative longitudinal movement, and clutch parts on the sections engageable to prevent relative turning between the sections and disengageable by the relative movement between the sections permitted by said means.

10. Well production equipment including a pump operating string comprising a multiplicity of screw threaded parts, and a safety joint for the string comprising two sections to be interposed in the string, screw threads on the sections for securing the sections to spaced parts of the string, a member releasably screw threaded with one section, means connecting the member with the other section for limited relative turning and limited relative longitudinal movement, and

clutch parts on the sections engageable to prevent relative turning between the sections and disengageable by the relative movement between the sections permitted by said means, the crests of the clutch parts being engageable for the transmission of axial movement between the sections in one direction when said means is operable to transmit axial movement between the sections in the other direction.

11. Well production equipment including a well pump operating string and a safety joint for the string comprising two sections interposed in the string, a member releasably screw threaded with one section, means connecting the member with the other section for limited relative turning and limited relative longitudinal movement, clutch parts on the sections adapted to mesh for the transmission of turning forces in both directions and movable out of mesh by the limited relative axial movement of the sections allowed by said means, the crests of the clutch parts being engageable by relative turning of the sections for the transmission of axial movement between the sections in one direction when said means is operable to transmit axial movement between the sections in the other direction, and spring means tending to turn one section relative to the other to bring said crests into engagement.

12. A safety joint for a pump operating string comprised of lengths connected by screw threaded joints, the safety joint including two sections interposed in the string and connected with adjacent lengths of the string, a member received in the two sections, screw threads releasably connecting the member with one section, said threads being pitched in the opposite direction to the threads of said joints, means limiting axial and turning movement between said member and the other section, clutch parts on the sections engageable upon relative axial and turning movement between the sections as allowed by said means and operable to transmit turning forces between the sections, said means allowing relative movement in excess of that required to engage and disengage the clutch parts so that torque built up in the string while the clutch parts are in mesh may suddenly turn the member a short distance and produce a jarring action to free said screw threads for easy unthreading.

13. Well production equipment comprising a well tubing having a drain port, a pump carried by the tubing, and a pump operating string extending into the tubing, the equipment being characterized by a sleeve in the tubing closing said port and movable to a position where the port is open, a joint interposed in the string releasable to allow withdrawal of the main portion of the string, a pair of blades projectable from said portion of the string and operable when projected to engage and move said sleeve, a pin on the lower portion of the string holding the blades retracted and freed from the blades upon the release of said joint, and spring means for projecting the blades.
